CLAIM

The ornamental design for a pruning tool, as shown and described.

DESCRIPTION

FIG. 1 is a perspective view of the pruning tool;
FIG. 2 is a top view of the pruning tool;
FIG. 3 is a right side view of the pruning tool;
FIG. 4 is a left side view of the pruning tool;
FIG. 5 is a bottom view of the pruning tool;
FIG. 6 is a front view of the pruning tool; and,
FIG. 7 is rear view of the pruning tool.

The broken lines showing in FIG. 5 illustrate portions of the pruning tool and form no part of the claimed design.
